UNITED STATES PATENT OFFICE.

SAMUEL W. RAYMOND, OF ADRIAN, MICHIGAN.

DOOR-OPERATING MECHANISM.

1,204,488.

Specification of Letters Patent.

Patented Nov. 14, 1916.

Application filed February 14, 1916. Serial No. 78,152.

To all whom it may concern:

Be it known that I, SAMUEL W. RAYMOND, a citizen of the United States of America, residing at Adrian, in the county of Lenawee, and State of Michigan, have invented certain new and useful Improvements in Door-Operating Mechanism, of which the following is a specification, reference being had therein to the accompanying drawings.

10 This invention relates to an opening and closing mechanism for doors, gates or other closures hinged or hung to swing in a horizontal plane and close a doorway or other opening.

15 The mechanism to be hereinafter described in detail has been especially designed for opening and closing the doors of garages, carriage and other vehicle houses, and its use necessitates a position which will not interfere with the passage of an automobile in and out of the garage.

20 The primary object of my invention is to provide an opening and closing mechanism for doors that may be operated at a point remote from the doors and associated with the opening and closing mechanism is a latch or locking device for holding the doors normally closed, but operable in synchronism with the mechanism, whereby the doors can 25 be expeditiously opened or closed.

Another object of my invention is to provide an opening and closing mechanism for doors which permit of one door being moved in advance of another door, whereby doors 30 having chamfered or mortised meeting edges may be properly closed.

Another object of my invention is to provide a novel mechanism for opening and closing sliding or rolling doors, the mechanism including a series of articulated levers that can be easily installed at the upper edges of the sliding doors to shift the same when desired.

35 A still further object of my invention is to provide a simple, durable and inexpensive door opening and closing mechanism that can be easily installed in a garage, in an overhead position, to open and close the doors by a single operation, which otherwise 40 would consume some time.

The above and other objects are attained by a mechanical construction illustrated in the accompanying drawings, wherein—

45 Figure 1 is a plan of the opening and closing mechanism in connection with a set of doors which are closed, the mechanism being

partly broken away; Fig. 2 is a similar view of the mechanism showing the doors in an open position; Fig. 3 is an elevation of the opening and closing mechanism showing the doors operated thereby in a closed position; Fig. 4 is a plan of a door opening and closing mechanism illustrating a slight modification of my invention, and showing hinged doors in a closed position; Fig. 5 is a similar view of the same construction showing the doors in an open position; and Figs. 6 and 7 are detail views of brackets.

50 As an example of an installation of the door opening and closing mechanism, there is shown a wall 1 having a doorway 2 adapted to be closed by a set of hinged doors 3 and 4.

55 Connected to the wall 1, above the doorway 2, is a skeleton bracket 5 providing two bearings 6 having a fixed relation relative to the wall 1 and supported in substantially the same horizontal plane as the upper edges of the doors 3 and 4. Pivotally connected to the bearings 6 are members 7 and the outer ends of said members are pivotally connected, by brackets 8, to the upper edges of the doors 3 and 4, adjacent the hinged edges thereof.

60 The confronting ends of the members 7 are pivotally connected by links 9 to the end of a lever 10 fulcrumed upon a three leg or spider bracket 11 secured to the wall 1 at one side of the skeleton bracket 5. The lever 10 extends to one side of the doorway 2 and the end lever has a pin 12 extending into the slotted end 13 of an operating rod 14, and by reciprocating this rod the lever 10 may be rocked upon its fulcrum and the members 7 actuated to open or close the doors 3 and 4.

65 The upper edge of the doorway 2, at the inner side of the wall 1, has a keeper 15 adapted to receive a latch 16 slidable in a guide or casing 17 connected to the upper edge of the door 3. The latch 16 is actuated by a spring held pivoted arm 18, carried by the door 3 and said arm is connected to a cable 19, connected to the slotted end 13 of the rod 14. The cable 19 represents a suitable flexible connection between the arm 18 and the rod 14 and said cable is trained over a sheave 20 and through a guide 21, both of which are on the door 3. By reference to Fig. 1, it will be observed that the slotted end 13 of the rod 14 permits of the cable 19 being pulled upon to shift the latch 16 to a released position before the extreme

end of the rod 14 engages the pin 12 to actuate the mechanism and swing the doors 3 and 4 to an open position. There is sufficient slack in the cable 19 to allow the 5 latch 16 to snap into the keeper 15 when the doors 3 and 4 are closed, and it is apparent that the rod 14 may extend to any desired location from which it is desired to operate the doors.

10 With the brackets 5 and 11 made of skeleton or spider form, the greater part of the mechanism can be made of light durable structural steel and comparatively few parts are required, consequently the wall 1 is 15 not subjected to any stresses or strain by reason of the weight of the opening and closing mechanism.

In Figs. 4 to 7 inclusive there is illustrated a modified form of door opening and closing mechanism. The hinged doors are designated 30 and 31. Above the doorway are brackets 32 pivotally supporting bearings 33 for members 34, and said members are pivotally connected to brackets 35 of the doors 30 and 31. The members are also pivotally connected to links 36 and these links extend toward the wall above the doors 30 and 31, in contradistinction to the links 9 of the preferred form of construction. The links 36 30 are pivotally connected to a lever 37 fulcrumed upon a one arm bracket 38 extending outwardly from the wall above the doors 30 and 31. An operating rod 39 is used in connection with the lever 37 and said operating rod is adapted to actuate a latch mechanism in conjunction with the door 31.

What I claim is:

1. In a door opening and closing mechanism, the combination with a wall having a 40 doorway, and a set of hinged doors normally closing said doorway, of brackets carried by the inner side of said wall above said doorway, members pivoted on two of said brackets and pivotally connected to the upper edges of said doors adjacent the hinged edges thereof, a lever fulcrumed on the other of said brackets, links connecting one end of said lever to said members, and an operating rod connected to the opposite end of said 45 lever.

2. In a door opening and closing mechanism, the combination with a wall having a doorway and a set of hinged doors normally closing said doorway, of brackets carried by the inner side of said wall above said doorway, members pivoted on two of said 55 brackets and pivotally connected to the upper edges of said doors adjacent the hinged edges thereof, a lever fulcrumed on the other

of said brackets, and having one end thereof connected to said members, an operating rod having a slotted end connected to the opposite end of said lever, and a latch adapted to hold said doors closed and connected to the slotted end of said operating rod to 60 be operated in advance of the mechanism when opening said doors.

3. In a door opening and closing mechanism, the combination with a wall having a doorway and a set of hinged doors normally closing said doorway, of brackets carried by the inner side of said wall above said doorway, bearings carried by two of said brackets, a member pivoted on each bearing and pivotally connected to the upper edge 70 of a door adjacent the hinged edge thereof, a lever fulcrumed on the other of said brackets and having an end thereof connected to said members, and means to facilitate operating said lever at a remote point 75 relative to said doors.

4. In a door opening and closing mechanism, the combination with a wall having a doorway, and a set of doors normally closing said doorway, of bearings supported 80 from said wall above said doorway, members supported by said bearings and connected to the upper edges of said doors, a fulcrumed operating lever supported from said wall and connected to said members 85 whereby said bell cranks can be simultaneously moved for opening and closing said doors, a latch mechanism adapted to hold said doors closed, means for moving said operating lever, and means actuated by the 90 last mentioned means for moving said latch mechanism in advance of the movement of said operating lever.

5. In a door opening and closing mechanism, the combination with a wall having a 100 doorway, and a set of doors normally closing said doorway, of brackets carried at the inner side of said wall above said doorway, members pivotally supported from two of said brackets and pivotally connected to the 105 upper edges of said doors, a lever fulcrumed on the other of said brackets, links connecting one end of said lever to said members, and means engaging the opposite end of said 110 lever adapted for moving said lever to open and close said doors.

In testimony whereof I affix my signature in presence of two witnesses.

SAMUEL W. RAYMOND.
